INDEX CARD

Friedrich Hiller, Cologne-on-the-Rhine, Germany

Application October 1, 1932, Serial No. 635,801

In Germany October 12, 1931

9 Claims. (Cl. 129—16.5)

The invention relates to index cards, i. e. to groups of cards lying over each other in echelon form, or sheets of paper, or pockets taking up same, suitably arranged for bookkeeping or similar purposes and so bound together that, in order to show the contents of the individual cards, the edges are formed in steps or echeloned with reference to each other, so that all the cards, leaves or pockets become simultaneously visible.

10 The subject of the invention is index cards of this kind whereby the echelon idea is carried into effect by means of strings or the like which are carried through a suitable selected hole out of a series of holes on the edge of each card.

15 In index cards of this kind, hitherto known, there is provided only one such string connection for every group of cards, and to get the cards in the echelon position rendering them simultaneously visible it is necessary to have the cards arranged in a plane surface in such a way that they can follow the movement of the string or like and in a parallel direction.

20 The subject of the present invention forms an elaboration of the means of movement serving to bind and move the parts of such index cards, which is an improvement of the mode of operation of visible index card systems in that it is not necessary to have a plane working surface to operate the cards. This is accomplished by the fact that the cord or other device for bringing the cards into the position of simultaneous visibility passes through holes punched in the single cards, not only on one side longitudinal edge, but on two parallel edges, the holes arranged at equal heights at opposite edges, by which the adjacent cards are echeloned by the distance of a line, or the distance required to be echeloned by each card, according to position in the same sense.

25 By this means it is accomplished that if both strings, cords, etc., are stressed simultaneously under the effect of gravity or other force acting on the cards, the cards are necessarily brought into a state of being parallel to each other when echeloned into the position of visibility, without 30 there being any need for touching any definite part of a guiding surface. By means of this more positive binding together of the single cards of each group, the handling of the cards in every respect is rendered easier without rendering more difficult accessibility to their writing surface. Besides this, there is obtained a further application of the echelon means since, by means of this idea, the cards can remain stored in an echeloned state permanently, so that their visible

borders are not spoilt by considerable echelon movements.

In the drawings:

Figure 1 is a pictorial representation of the cards belonging to a group in a closed position.

Figure 2, shown likewise pictorially, this group of cards echeloned out for simultaneous revelation of contents, with lineable borders or edges.

Figure 3 is a section through Figure 1, at right angles.

Figure 4 is a section on the same plane as Fig. 3 but showing the cards in offset position.

Figure 5 is a front view of the cards echeloned out with parallel sides.

Figure 6 is a section on line VI—VI of Figure 5.

Figure 7, a corresponding section through the closed cards.

Figure 8 is a perspective view of the application of the invention to a group of filed papers in closed position.

Figure 9 is a perspective view similar to Fig. 8 showing the covers in open position.

Figure 10, a section through Fig. 9 at the string.

Figure 11 is an interior view of the front cover 25 of the file of Fig. 10.

Figure 12 shows a side view of a number of files in closed and echeloned position in a suitable container, as per Figs. 8-11 ready for use.

In the form shown in Figs. 1-4 of the device, 30 the individual cards 1 of the pack are enclosed between two flat covers preferably of stout cardboard or pasteboard, or wood or the like, having the same height as these cards. The rear cover 2, is provided at its upper edge with a protruding 35 hand grip 4 serving at the same time to label the contents. Near its lower edge at uniform distance from the two vertical edges there are fixed two binders 5, 6 on which the cards are filed by means of a pair of holes 7-8 equally high by 40 series of holes, disposed along the vertical edges of the cards uniformly.

The arrangement of the cards on the binding string is such that each card is fixed by a pair of holes one higher or lower than those of adjacent cards. For example, the front ends of the two binders are led through holes near the upper edge of the front cover 3 and in the drawings are secured to handles 9 serving to operate same.

If one grasps the two rings 9 in the closed 50 position of Figure 1, of the closed bundle and pulls upwards, the cards will be so displaced that successive pairs of holes register, and at the same time a portion of each card equal to the vertical distance between two holes will be displaced ver- 55

tically. If one now lays this bundle of cards in echelon form on a table surface, one can, as Figure 2 shows, by lowering the front cover 3, have a look at the first card 1, and make it accessible for writing upon. Similarly the subsequent cards on the two binding strings 5, 6 can be pushed under the front cover 3 and thereby the required card, which is easily found from the inscriptions on the free edges, is made accessible for inspection and writing upon. The backs of the cards are similarly rendered accessible by turning the cards around.

The form shown in Figs. 5-7 of the group of cards distinguishes itself from that shown in Figs. 1-4 fundamentally only in that instead of using binders consisting of round string 6, 5 flat bands 10, 11 are employed, which consist preferably of thin sheet metal, for example, watch spring steel of similar stuff. The back end of each of the bands 10-11 is preferably fixed in the form of a joint in the vertical direction on the lower end of the back cover plate 2 like a hinge. The front ends of the bands each terminate in an eye 12 and is secured by a piece of wire 13, which, by means of two sheet metal hinges 14 on the upper end of the front cover plate 3, is fixed so that it can be drawn out.

Provided no alteration in the mutual position of the cards of the single groups, and thereby no alteration of the holes, is contemplated, the holes not required can be omitted, that is to say, on each card there will be only two border holes so positioned as to provide the required echelon of the free edges.

As in the case of the index cards, such as can be moved vertically, one can fashion each one of the cards as a pocket, open at the top, for insertion of the actual account sheets, and, if preferred, one can use as a backing for such a pocket, a stout back sheet which, according to the simple sheets to be inserted, is punched and filed on the two bands 10 and 11 with suitable holes and the upper edge of which, by virtue of the staggered holing, can be used for designating or labelling the accounts.

In the form shown in Figs. 8-12 of the invention, the arrangement is such that in this case the leaves formed as pockets to contain account sheets of each group of cards are closed in echelon form. For this purpose the backs of both covers 15 and 16 are lengthened by the sum of the amounts of echelon of each pocket at the upper border with respect to the filing bands 10-11 which are connected between the front cover 16 and rear cover 15, the cover being connected by means of a flexible strip 17 of leather or suitable fabric.

The two elastic filing bands 10, 11 are preferably of thin steel, each being terminated at the front with a button 18 sliding in a vertical slot 19 of the front cover parallel to the plane of the appropriate filing holes of the cards or pockets. The length of the two filing bands is so proportioned that two connected supporting covers can be opened to a sufficiently wide angle to get at the cards or pockets over the front cover.

In the open position according to Figs. 9 and 10, the cards or pockets which, in the extended position rest on these filing bands, are freely movable backwards and forwards along same. By this means one can make accessible the individual card pockets for removal and insertion of the sheets to be laid in same, these pockets being formed by a piece of strong paper 20, stuck on at the lower edge of each card 1. In closing the

two covers 15 and 16, the two buttons 18 of the filing bands 10 and 11, rise in their slots. When these covers are closed the pliability of the bands permits them to bend easily and without permanent alteration of form, but bending does occur such that the cards or pockets, in taking up their normal echeloned position make only a slight relative vertical displacement. By this is obtained a greater life of the pockets.

In use the visible groups of cards, the necessary number are preserved in open containers (boxes), the side walls 21 of which are arranged at a distance apart the width of the cards, while the front and back covers 22, 23 are hinged with hinges (24) at their lower ends and can be held in position by means of a pair of slot rings 25 attached to both sides. The files in the preservation box can be leaned in a slightly sloping position partly against the front, 22, and partly against the back cover 23, so that between these two groups there is room to open the foremost file of both groups and render it accessible, as Figure 12 shows.

I claim:

1. The combination with a series of index cards each having on opposite side edges a row of spaced openings, said rows extending parallel to said side edges, and a pair of flexible strands each extending through one of the openings of a respective row, the openings of successive cards receiving said strands being successively offset upwardly from the bottom of the rearmost card of the series whereby like marginal top portions of the cards are displaced upwardly from the front to the rear of the series upon tensioning said strands, said strands being each free from knots between its ends.

2. The combination with a series of index cards each having on opposite side edges a row of spaced openings, said rows extending parallel to said side edges, and a pair of flexible strands each extending through one of the openings of a respective row, the openings of successive cards receiving said strands being successively offset upwardly from the bottom of the rearmost card of the series whereby like marginal top portions of the cards are displaced upwardly from the front to the rear of the series upon tensioning said strands, the holes at one side of each card being respectively in horizontal alignment with the respective holes on the opposite side of the card whereby tensioning of the two strands effects positioning of the marginal edges of the cards in parallelism, said strands being each free from knots between its ends.

3. The combination with a series of index cards each having on opposite side edges a row of spaced openings, said rows extending parallel to said side edges, a pair of flexible strands each extending through one of the openings of a respective row, the openings of successive cards receiving said strands being successively offset upwardly from the bottom of the rearmost card of the series whereby like marginal top portions of the cards are displaced upwardly from the front to the rear of the series upon tensioning said strands, and a covering folder for said series of cards having front and rear members hingedly connected at their lower edges, said strands having their front and rear members attached respectively to the front and rear members of said folder.

4. The combination with a series of index cards each having on opposite side edges a row of spaced openings, said rows extending parallel

- to said side edges, a pair of flexible strands each extending through one of the openings of a respective row, the openings of successive cards receiving said strands being successively offset upwardly from the bottom of the rearmost card of the series whereby like marginal top portions of the cards are displaced upwardly from the front to the rear of the series upon tensioning said strands, the holes at one side of each card being respectively in horizontal alinement with the respective holes on the opposite side of the card whereby tensioning of the two strands effects positioning of the marginal edges of the cards in parallelism, and a covering folder for said series of cards having front and rear members hingedly connected at their lower edges, said strands having their front and rear members attached respectively to the front and rear members of said folder.
5. The combination with a series of index cards each having on opposite side edges a row of spaced openings, said rows extending parallel to said side edges, a pair of flexible strands each extending through one of the openings of a respective row, the openings of successive cards receiving said strands being successively offset upwardly from the bottom of the rearmost card of the series whereby like marginal top portions of the cards are displaced upwardly from the front to the rear of the series upon tensioning said strands, a supporting cover at the rear end of the system to which the rear ends of the two strands are attached in the plane of elevation of the lowermost perforation of each of the two rows of perforations and spaced in accordance with the spacing of said rows of perforations, and a supporting cover at the front end of the system to which the front ends of the two strands are attached.
6. The combination with a series of index cards each having on opposite side edges a row of spaced openings, said rows extending parallel to said side edges, a pair of flexible strands each extending through one of the openings of a respective row, the openings of successive cards receiving said strands being successively offset upwardly from the bottom of the rearmost card of the series whereby like marginal top portions of the cards are displaced upwardly from the front to the rear of the series upon tensioning said strands, the holes at one side of each card being respectively in horizontal alinement with the respective holes on the opposite side of the card whereby tensioning of the two strands effects positioning of the marginal edges of the cards in parallelism, and means for simultaneously tensioning said strands.
7. The combination with a series of index cards each having on opposite side edges a row of spaced openings, said rows extending parallel to said side edges, a pair of flexible strands each extending through one of the openings of a respective row, the openings of successive cards receiving said strands being successively offset upwardly from the bottom of the rearmost card of the series whereby like marginal top portions of the cards are displaced upwardly from the front to the rear of the series upon tensioning said strands, the rear ends of the strands being attached to a rigid rear cover in the plane of elevation of the lowermost perforation of each of the two rows of perforations, and the front ends of the strands being attached to a rigid front cover in the plane of elevation of the uppermost perforation of each of the two rows of perforations, whereby the length of each of the strands is at least as large as the diagonal distance between the lowermost perforation of a row of perforations of the rearmost card and the uppermost perforation of the corresponding row of perforations of the foremost card when the cards are in superposed position.

FRIEDRICH HILLER. 55
